SPORTS HELMET

Creighton J. Hale, Williamsport, Pa., assignor to Little League Baseball, Inc., Williamsport, Pa., a corporation of New York

Filed Apr. 21, 1959, Ser. No. 55,593

Term of patent 14 years

(Cl. D3—13)

Fig. 1 is a perspective view illustrating my new design for a sports helmet.

Fig. 2 is a front elevational view thereof.

Fig. 3 is a side elevational view thereof, the side opposite thereto being identical in appearance.

I claim:

The ornamental design for a sports helmet, as shown and described.
